ACCESSORIES FOR TOILET FLUSH TANK

Albert N. Porter, Tulsa, Okla.

Application October 2, 1956, Serial No. 613,443

2 Claims. (Cl. 4—57)

This invention relates to a toilet flush tank.

The object of the invention is to provide a toilet flush tank which includes an improved lift rod and guides therefor whereby the toilet flush tank will operate more efficiently.

A still further object of the invention is to provide a toilet flush tank which is provided with an overflow pipe, a ball, and a lift rod which has its lower end connected to the ball, and the lift rod being longer than the usual lift rods whereby two guide members can be arranged in engagement with the lift rod so as to insure that the lift rod will remain in a vertical position as it moves up and down so that the ball will properly seat during the operation or movement thereof.

A further object of the invention is to provide flush tank accessories which are extremely simple and inexpensive to manufacture.

Other objects and advantages will be apparent during the course of the following description.

In the accompanying drawings, forming a part of this application, and in which like numerals are used to designate like parts throughout the same.

Figure 1 is an elevational view illustrating a portion of a toilet flush tank, and with parts broken away and in section and showing the accessories of the present invention thereon.

Figure 2 is a top plan view illustrating the overflow pipe and upper guide member.

Figure 3 is a sectional view taken on the line 3—3 of Figure 1.

Figure 4 is a sectional view taken on the line 4—4 of Figure 1.

Figure 5 is an elevational view illustrating a modified lift rod.

Figure 6 is a fragmentary elevational view showing the lift rod of Figure 5 but taken at right angles thereto.

Figure 7 is a view similar to Figure 5 but showing a still further modified lift rod.

Figure 8 is a fragmentary view taken at right angles to the view shown in Figure 7.

Figure 9 is a fragmentary elevational view showing a modified upper guide on the upper end of the overflow pipe.

Figure 10 is a top plan view of the assembly shown in Figure 9.

Figure 11 is a sectional view taken on the line 11—11 of Figure 10.

Referring in detail to the drawings, and more particularly to Figures 1 through 4 of the drawings, the numeral 10 indicates or designates the usual overflow pipe which is mounted in the toilet flush tank, while the numeral 11 designates the usual seat, the ball 12 being mounted for movement into and out of closing relation with respect to the seat 11. Extending outwardly from the overflow pipe 10 is a lower guide 13.

The numeral 14 designates the lift rod of the present invention which is longer than the conventional lift rods,

2

and the lift rod 14 has its lower end arranged in threaded engagement with the ball 12. The intermediate portion of the lift rod 14 is coiled so as to define an eye 16. The numeral 17 designates the usual trip arm which is provided with apertures or openings 18 whereby a link 19 can have its upper end 20 arranged in engagement with one of the openings 18. The link 19 is further provided with a lower portion 21 which receives the lift rod 14, the portion 21 of the link 19 being arranged below the eye 16 so that as the trip arm 17 is moved, the lift rod 14 can be raised to thereby unseat the ball 12 in the seat 11.

There is further provided an upper guide which is indicated generally by the numeral 22, Figures 1 and 3 and Figure 2. The upper guide 22 includes a first portion 23 which extends downwardly into the upper end of the overflow pipe 10, and formed on the lower end of the portion 23 is a triangular section 24. The guide 22 further includes a curved portion 25 which engages the upper edge of the overflow pipe 10, and the curved portion 25 terminates in a downwardly extending second portion 26 which is arranged on the outside of the pipe 10. The lower end of the portion 26 terminates in a curved portion 27, and the portion 27 terminates in an upstanding third portion 28, the portion 28 terminating in a horizontal portion 29, there being an eyelet or loop 30 on the end of the portion 29 for receiving the upper end of the lift rod 14.

Referring to Figures 5 and 6 of the drawings there is shown a modified lift rod which is indicated generally by the numeral 31. The lift rod 31 may be made of two pieces or two sections 32 and 33 instead of being made of one piece of material as is the lift rod 14 shown in Figure 1. The lift rod 31 thus includes a lower section 32 and an upper section 33. Formed on the upper end of the lower section 32 is a loop or eye 34, while the lower end of the upper section 33 is provided with a flattened portion 35 which has a threaded aperture therein. A suitable securing element such as the bolt 36 extends through the loop 34 and through the threaded aperture in the flattened portion 35 for maintaining the upper and lower sections of the lift rods connected together. The lower end of the upper section 33 is further provided with a pair of spaced parallel fingers 37 which are arranged below the loops 34 so as to help maintain the parts in their proper assembled positions.

Referring to Figures 7 and 8 of the drawings, there is shown a still further modified lift rod 38 which is of two piece construction instead of the one piece construction shown in Figure 1. The lift rod 38 includes the lower section 39 and an upper section 40, there being a loop 41 on the upper end of the section 39, there being an offset loop 42 on the lower end of the upper section 40. A suitable securing element such as a bolt 43 extends through the pair of loops 41 and 42. The numeral 44 indicates a bracket which includes a web 45 that may be provided with a threaded aperture for receiving an end of the bolt 43, and the bracket 44 further includes upper and lower fingers 46 and 47 which are arranged on opposite sides of the loops for helping to maintain the parts in their proper assembled position.

Referring to Figures 9, 10 and 11 of the drawings, there is shown a modified upper guide which is indicated generally by the numeral 48, and the upper guide 48 is adapted to be mounted on the upper end of the overflow pipe 10. The upper guide 48 includes a first portion 49 which extends downwardly into the interior of the overflow pipe 10, and the lower end of the first portion 49 is shaped to define a wide lower portion 50. Extending outwardly from the upper end of the first portion 49 is a second portion 51 which extends across the upper edge

of the overflow pipe 10, there being a third portion 52 extending downwardly from the portion 51. The lower end of the portion 52 terminates in a curved section or portion 53 which abuts the outer surface of the overflow pipe 10, and extending upwardly from the curved portion 53 is a fourth portion 54 which terminates in an outwardly extending fifth portion 55. A curved portion 56 extends from the outer end of the portion 55 and terminates in a sixth portion 57, the portion 57 being provided with a hook 58 which is mounted for movement into and out of engagement with the portion 52 as shown by solid and broken lines in Figure 9.

In Figures 9, 10 and 11 the numeral 59 designates an adjustable body member which includes a pair of spaced parallel vertically disposed side walls 60. The side walls 60 are provided with grooves 61 in their upper edges for at times receiving the portion 57 of the guide. The walls 60 are further provided with lower grooves 62 for engagement with the portion 55 of the guide. The body member 59 further includes an end wall 63 which has a lip or ear 64 extending outwardly therefrom, and the lip 64 is provided with a circular opening 65 for slidably receiving the upper end of a lift rod such as one of the previously described lift rods.

From the foregoing it is apparent that there has been provided accessories for use with a toilet flush tank whereby the efficiency of the toilet flush tank will be improved. In Figures 1 through 4 there is shown one form of the invention and in use, the trip arm 17 can be actuated in the usual manner to thereby raise the link 19 so that the portion 21 of the link 19 will engage the lower surface of the eye 16 to thereby raise the lift rod 14. As the lift rod 14 moves upward, it raises the ball 12. It is to be noted that the lift rod 14 is longer than usual so that two guides 13 and 22 are arranged in engagement with the lift rod so as to insure that the lift rod will remain in a true vertical position as it moves up and down and this will insure that the ball 12 returns to its proper position on the seat 11 after each movement thereof. Thus, with previous lift rods, the lift rod was shorter so that only one guide engaged the lift rod whereby the lift rod had a tendency to move out of a true vertical position so that the ball 12 could readily get out of position so that it would not properly seat. With the present invention these difficulties are overcome. Also in Figures 1, 2 and 4 there is provided the guide 22 which is supported on the upper end of the pipe 10, and the guide 22 includes the portion 29 which has the loop 30 thereon for slidably receiving the upper end of the lift rod 14. The lift rod 14 is of one piece construction.

Referring to Figures 5 and 6 of the drawings, there is shown a modified lift rod which is adapted to be used in lieu of the lift rod 14. The remaining parts of the apparatus may be the same. The lift rod shown in Figures 5 and 6 is indicated by the numeral 31 and includes the upper section 33 and lower section 32 which are connected together as previously described. The portion 21 of the link 19 is adapted to abut the fingers 37 as the trip arm 17 is actuated so that the lift rod will be raised. As shown in Figure 5, the lower end of the lift rod may be threaded for engaging the ball 12.

In Figures 7 and 8 there is shown a still further modified lift rod which is indicated generally by the numeral 38, and the lift rod 38 again has two sections 39 and 40 connected together so as to provide a long lift rod which can be engaged by the upper and lower guide whereby the lift rod will be maintained in its true vertical position as it moves.

Referring to Figures 9, 10 and 11 of the drawings, there is shown a modified guide which is indicated generally by the numeral 48, and the guide 48 is adapted to be used in lieu of the guide 22. The guide 48 is constructed so that the hook 58 can be disengaged from the portion 52 whereby the portion 57 of the guide can move from the solid line position shown in Figure 9 to the

broken line position shown in Figure 9 so that the body member 59 can be shifted to different positions in order to properly align the opening 65 with the upper end of the lift rod. After the body member 59 has been moved to its proper position, the hook 58 is again moved to the solid line position shown in Figure 9 so that the body member 59 will be retained immobile in its adjusted position.

When making the lift rod of the present invention, the standard lift rod may be used as the lower section and then an additional section may be connected to the upper end of the lower section so as to provide the longer lift rod. Furthermore, a conventional flush tank has only one guide for the lift rod but with the present invention two guides are used. Thus, the ball will make a perfect seat each time, the upper guide being clamped on top of the overflow pipe 10. Since the lift rod passes through the upper and lower guides, it will move straight up and down which will insure that the ball will have a perfect seat each time. The parts can be made of any suitable material and in any shape or size. Thus, with the present invention the ball 12 will effectively close off the water so that there will be no leakage of water around the ball. The hook 58 can be released until the body member 59 is adjusted then the hook 58 is replaced. As previously described, the present invention can be used on existing flush tanks since an extension or upper section can be connected to the lower lift rod section which is already on the toilet flush tank. The bolts such as the bolts 43 and 36 can be readily removed or replaced in the event that the lift rod is to be disassembled. The present invention can be installed as new equipment in toilet flush tanks, or else existing equipment in the tank can be modified in accordance with the present invention. Since most difficulties which arise when using toilet flush tanks are due to the ball not properly seating, the present invention will greatly improve the efficiency and usefulness of the flush tank. The guide 22 or the guide 48 is constructed so that there are a plurality of bearing points such as the points 24 and 27 whereby accidental shifting of the guide will be prevented.

I claim:

1. In a flush tank, an overflow pipe, a seat spaced from said overflow pipe, a ball mounted for movement into and out of closing relation with respect to said seat, a lower guide extending outwardly from said overflow pipe and secured thereto, a lift rod having its lower end threadedly engaging said ball and said rod extending through said guide, a portion of said lift rod being coiled intermediate its ends to define an eye, a movable trip arm provided with a plurality of apertures therein, a link having one end arranged in engagement with one of the apertures in said trip arm and the other end of said link being arranged in engagement with said lift rod below said eye, an upper guide extending outwardly from the upper end of said overflow pipe and engaging the upper end of said lift rod, said upper guide comprising a first portion extending downwardly into the upper end of said overflow pipe and terminating in a triangular lower section, the upper end of said first portion defining a curved portion engaging the upper edge of said overflow pipe and said curved portion terminating in a second portion extending downwardly along the outer surface of said overflow pipe, the lower end of said second portion terminating in a curved portion abutting the outer surface of said overflow pipe, said last named curved portion terminating in an upstanding third portion, said third portion terminating in a horizontally disposed fourth portion, the outer end of said fourth portion being provided with an eyelet for receiving the upper end of said lift rod.
2. In a toilet flush tank, an overflow pipe, an upper guide extending outwardly from the upper end of said overflow pipe and comprising a first portion extending downwardly into the upper end of said overflow pipe and

terminating in a triangular lower section, the upper end of said first portion defining a curved portion engaging the upper edge of said overflow pipe and said curved portion terminating in a second portion extending downwardly along the outer surface of said overflow pipe, the lower end of said second portion terminating in a curved portion abutting the outer surface of said overflow pipe, said last named curved portion terminating in an upstanding third portion, said third portion ter-

minating in a horizontally disposed fourth portion, the outer end of said fourth portion being provided with an eyelet for receiving the upper end of a lift rod.
